UNITED STATES PATENT OFFICE

OTTO M. SUMMERS, OF DAYTON, OHIO, ASSIGNOR, BY MESNE ASSIGNMENTS, TO FRIGID-AIRE CORPORATION, A CORPORATION OF DELAWARE

REFRIGERATING APPARATUS

Application filed July 19, 1926. Serial No. 128,420.

The present invention relates to pressure responsive electric switches, and more particularly to switches for controlling electrically operated refrigerating apparatus.

One of the objects of the present invention is to provide for the quick and positive operation of the movable switch contact into and out of engagement with the stationary contact, by the use of a simplified mechanism which may be produced at relatively low cost.

Another object of the invention is to provide in a more simple manner independent adjustments of the pressures at which the switch contacts are engaged and separated.

One manner of carrying out the foregoing objects is to provide a contact operating member and a cooperating actuating member and provide for translatory, relative movement between these members whereby the movable contact is actuated in a certain direction when the members are in a certain relative position, and is actuated in another direction after a certain translatory, relative movement has taken place. An adjustable, mechanical resistance element is rendered effective to resist said translatory movement throughout a certain portion of said movement in one direction and then is rendered ineffective throughout another portion of said movement in the same direction. A second adjustable mechanical resistance element is used to oppose translatory movement in the opposite direction. Thus, independent adjustments may be made for the purpose of setting the switch to close at a certain high pressure corresponding to a certain high temperature in the cooling unit or chamber, and to open at a certain low pressure corresponding to a certain low temperature.

The present invention contemplates the use of a pressure operated device for actuating this switch and in this invention a collapsible pressure responsive device such as a metal bellows is utilized. Due to the manufacture of this type of device, the tension of all are not uniform. One of the objects of the present invention is to provide simple means for adjusting the collapsible device.

Further objects and advantages of the

present invention will be apparent from the following description, reference being had to the accompanying drawings, wherein a preferred form of embodiment of the present invention is clearly shown.

In the drawings:

Fig. 1 is a top plan view of the improved switch.

Fig. 2 is a partly elevational and partly sectional view of the switch, the sectional portion being taken on line 2-2 of Fig. 1.

Figs. 3 and 6 are fragmentary views, partly in section each showing the operating mechanism in different positions from that shown in the other figures.

Fig. 4 is a fragmentary view partly in section as the bottom portion of the switch, the view being taken looking in the direction of arrow 6 of Fig. 2, and

Fig. 5 is a view similar to Fig. 2 but showing operating mechanism in a different position from that shown in Fig. 2.

Fig. 7 is an end view of the switch.

Referring to the drawings, there is shown a frame 20 having downwardly bent supporting legs 21 and a platform 22 which carries the entire switch mechanism. At one end of the platform 22 there are a plurality of perforations, each including a relatively large opening 23 and a relatively small opening 24. The openings 23 are each adapted to receive one of the legs 25 of a cage 26. The legs 25 are constructed of resilient material and normally tend to bend outwardly and each is provided with a cut-a-way portion 27 adapted to form shoulders 28. Centrally located with respect to the openings 23, the platform 22 is provided with an opening 29 which merges into a larger opening 30. A metal bellows 31 is supported by the platform 22 and is provided with a nipple 32 which extends through the opening 29. A fluid conductor 33 connects the interior of the bellows with a coupling 34. Bellows 31, fluid conductor pipe 33, and coupling 34 are constructed as a sub-assembly, the opening 30 within platform 22 being of such diameter so as to permit the coupling 34 to be inserted therethrough. After the coupling 34 and pipe 33 have been inserted downwardly

55

65

75

80

85

90

95

100

through the opening 30, the bellows 31 and nipple 32 are shifted to the right to the position shown in the drawings. The cage 26 is then placed in position by first bending the legs 25 inwardly and then inserting same within the openings 23 until the cut-a-way portions thereof are opposite the opening 24; the legs are then permitted to spring outwardly whereby the cut-a-way portions move into the opening 24. The shoulders 27 and 28 on opposite sides of the platform 22 will prevent the upward or downward movement of the cage 26. A plate 35 is mounted on the underside of the platform 22 and is of sufficient diameter to prevent the lateral displacement of the legs 25. Plate 35 is provided with connecting openings 36 and 37, the opening 36 being adapted to receive the nipple 32 and the opening 37 being of sufficient diameter to receive the coupling 34 whereby the plate may be placed in position from the bottom side of the platform 22. A nut 38 is utilized for holding the plate 35, the nipple 32, and likewise the bottom portion 40 of the bellows 31 in position. The upper part of the cage 26 has a shoulder 42 for limiting the movement of the bellows thus preventing abnormal expansion of bellows 31. The cage also carries a plurality of ears 43 which carry a pin 44, upon which an operating member or lever 45 is pivotally mounted. The operating member 45 is pivotally connected by a pin 46 to the top wall 47 of bellows 31 and is adapted to be moved upwardly and downwardly in response to the pressure within the bellows 31.

The opposite end of platform 22 carries an inverted U-shaped bracket, or yoke 50. A roller bracket 51 is pivotally mounted upon a pin 52 carried by the yoke 50. A spring 53 is wound around the pin 52 and tends to yieldingly move the roller bracket 51 to the right as viewed in the drawings. Roller bracket 51 carries a roller 55 which is arranged to cooperate with camming surfaces 56 and 57 of a lever 58 which lever is pivotally mounted at 59 upon the operating member 45. Lever 58 comprises two sheet metal strips 60 which are spaced from one another by a spacer rivet 61 and by a member 62 having the camming surfaces 56 and 57. These strips 60 are located on opposite sides of the arm 45. The end of the lever opposite the member 62 carries a link 64, which link is connected by clips 65 with a contact 66. Contact 66 is pivotally mounted at 67 upon a plate 68 carried by an insulating block 69. The contact 66 is also provided with a stop member 70 adapted to engage the block 69 to limit the upward movement of contact 66. A non-arcing contact 71 is carried by a leaf spring 72 which in turn is secured to the contact 66 and spring 72 normally tends to maintain the non-arcing contact 71, in the position relative to contact 66, as shown in Figs. 2 and

6. The insulating block 69 also carries a contact 74 adapted to be engaged by contacts 66 and 71. Wires 75 and 76 are connected respectively with contacts 66 and 74.

The top wall 78 of yoke 50 carries a screw threaded bushing 79 held in place by nut 80. Bushing 79 is arranged to receive a plunger 81 having a shoulder 82 for limiting the downward movement thereof. Bushing 79 screw threadedly carries a cap 83, and a spring 84 is interposed between the cap 83 and the shoulder 82 and normally tends to move the plunger downwardly. Plunger 81 lies in the path of the movement of a head 85 of operating member 45.

A rod 87 extends through an opening in platform 22 and is pivotally connected at 88 with the member 45. Adjusting nuts 89 and 90 co-operate with the rod 87 and are located on the opposite sides of platform 22. A spring 91 is interposed between nut 89 and platform 22 and a spring 92 is interposed between nut 90 and platform 22. Spring 91 may be used to assist the bellows 31 in the upward movement of lever 45 or the spring 92 may be used to resist the movement of bellows 31. Due to manufacture, some bellows may have different tension than others. Therefore, it may be necessary to assist the bellows, or it may be necessary to resist the bellows. When it is necessary to aid the bellows, the nuts 90 are moved to release the tension of spring 92. Then by screwing the nuts 89 downwardly the tension of spring 91 can be increased, thus assisting the bellows. However, if the tension of the bellows per se is greater than that desired, the nuts 89 are screwed upwardly to render the spring 91 ineffective. Then, the nuts 90 are screwed upwardly to increase the tensions of spring 92 so that said spring resists the tension of the bellows. In this manner the tension of the bellows is readily regulated.

The present invention is particularly adaptable for controlling system in which it is desirable to provide independently high and low pressure adjustments, such as a refrigerating system. One particular use of this switch would be to connect the switch so that the bellows 31 would be responsive to the pressure within the low pressure side of a refrigerating system, the switch being adapted to interrupt the circuit to a compressor driving motor when the pressure within the low pressure side attains a certain low value and to complete the circuit to the motor when the pressure within the low pressure side attains a certain high value.

The operation of the switch is as follows, considering that the contact 66 has just separated from contact 74 the switch mechanism will be in a position substantially as shown in Fig. 2. As the pressure increases within the bellows 31 the lever 45 will be moved upwardly. The spring pressed plunger 81 lying

70

75

130

within the path of movement of the head 85 of lever 45 will restrain the upward movement of lever 45. As the member 45 moves upwardly the lever 58 will be moved translatedly upwardly. The stop 70 of the contact 66 being in engagement with block 69, will limit the upward movement of that end of the lever 58 which carries the link 64, then, on further upward movement of member 45, lever 58 will 10 pivot about the connecting pin 95, between link 64 and lever 58. This movement of lever 58, will cause the camming surface 56 to move the roller bracket 51 toward the left. When the apex of member 62, which is formed by 15 the surfaces 56 and 57, engages the roller 55 the levers 58 and 45 will be substantially in position shown in Fig. 6 in which position contact 66 is still separated from contact 74. Upon further upwardly movement of the 20 levers 45 and 58 the camming surface 57 will be moved into engagement with the roller 52 at which time spring 53 will exert its yielding force to rotate the lever 58 in a clockwise direction, and, since the lever 58 is free to 25 rotate, the roller acting on camming surface 57 will cause contact 66 to quickly engage contact 74. With the construction and arrangement of pivoted contact 66, link 64, lever 58 and fulcrum pin 59 relative to one another, 30 as shown, the spring 53 exerts its yielding force to firmly maintain contact 66 in engagement with contact 74, as shown in Fig. 5.

As the pressure within the bellows 31 recedes, the member 45 will move downwardly 35 (see Fig. 5) and that end of lever 58, which is connected with link 64, is held substantially stationary because contact 74 limits the downward movement of contact 66 and likewise link 64. Therefore, with further downward movement of member 45, lever 58 will 40 pivot about pin 95. The camming surface 57 will then move downwardly over roller 55 and when the apex of member 62 moves beyond the roller, spring 53 will co-operate with surface 56 to rotate lever 58 about its fulcrum pin 59. The tension of spring 53 is such as to 45 quickly rotate lever 58 thereby suddenly separating contacts 66 and 71 from contact 74. Non-arcing contact 71 will separate from contact 74 after contact 66 thus preventing the 50 burning of contacts 66 and 74. When the apex of member 62 engages the roller 55, a condition arises in which the spring 53 will not urge lever 58 in either direction and there 55 may be a tendency for lever 58 to oscillate. This oscillating movement, however, is not imparted to contacts 66 and 71 and said contacts are not separated from contact 74 until the apex has moved beyond the roller 55 at 60 which time surface 56 will engage roller 55 to function as previously stated. Fig. 3 shows the relative relations of the elements just after the apex has moved downwardly beyond the roller 55. Referring to this Fig. 3 65 it is apparent how the contacts 66 and 71 are

maintained firmly against contact 74. A relative large hole 96 is provided in link 64 for receiving a pin 97, by which the link 64 is connected with clips 65 of contact 66, which pin 97 is free to move vertically within said hole 96. A hole 98 is also provided within the link 64 and is disposed transversely to hole 96 and adapted to receive a spring 99. Spring 99 is disposed between the top of hole 98 and pin 97 and urges pin 97 and likewise contact 66 downwardly. By virtue of this construction, the spring 99 maintains contact 66 in engagement with contact 74 although the lever 58 is in such a position with respect to roller 55 that it tends to oscillate. 70

It is apparent from the description and particularly Figs. 3 and 6 that a switch has been provided in which contacts are engaged and separated quickly. This is accomplished by providing a floating fulcrum pin 59 for the lever 58 whereby the lever 58 is translatedly moved relative to the roller 55. With this construction there is provided mechanism in which a lever and an actuating roller have different "dead center" positions when the lever is translatedly moved in opposite direction. In this manner one "dead center" position is attained while the contacts are separated and just previous to their engaging movement and a second "dead center" position is attained while the contacts are still in engagement and are about to be separated. Thus the movable contact is retained in either of its two positions until the actuating mechanism therefor has moved beyond "dead center" position. In this manner quick action of the contact in either direction is insured. 80

By utilizing mechanism in which the fulcrum point (pin 59) must be moved to a certain position before the contact actuating lever is moved to actuate the contact and which must be moved to a different position in order to reverse the movement of said lever, it is possible to provide for independent high and low pressure adjustments. During the 105 latter part of the downward movement of member 45 (see Figs. 2 and 5), the plunger is not in engagement with the member 45. Therefore, spring 84 is not effective and the pressure at which the contacts separate can 110 be regulated by either of springs 91 and 92. During the upward movement, however, member 45 engages plunger 81. Thus the pressure at which the contacts close is regulated by the adjustment of the tension of 115 spring 84. In this manner the switch can be adjusted so that the contacts can be closed at any desired pressure independently as to the pressure at which the contacts are open and, vice versa. To adjust the switch the 120 spring 91 or 92 is set so that the contacts are opened at the desired pressure within the bellows 31. Then spring 84 is set so that the contacts are closed at the desired pressure 125 within the bellows 31. 130

While the form of embodiment of the present invention as herein disclosed, constitutes a preferred form, it is to be understood that other forms might be adopted, all coming within the scope of the claims which follow.

5. What is claimed is as follows:

1. A switch comprising, in combination, a contact actuating lever member, an actuating member for the lever member, one of said members having a plurality of camming surfaces, and the other of said members being adapted to cooperate with one of the camming surfaces and thereby tending to yieldingly maintain the lever member in a certain 10 position throughout a certain bodily movement of one of said members with respect to the other and being adapted to cooperate with another of said camming surfaces for quickly rocking said lever member when the 15 members are relatively bodily moved to a certain position, and means for bodily moving the lever member relative to the actuating member.

2. A switch comprising, in combination, a contact actuating lever member having a plurality of camming surfaces, an actuating member adapted to cooperate with one of the camming surfaces and thereby tending to yieldingly maintain the lever member in a certain 20 position throughout a certain bodily movement of one of said members with respect to the other and being adapted to cooperate with another of said camming surfaces for quickly rocking said lever member when the members are relatively bodily moved to a certain position, and means for bodily moving the lever member relative to the actuating member.

3. A switch comprising, in combination, a contact actuating lever member, mechanism including an actuating member adapted to yieldingly maintain said lever member in a certain position through a certain bodily movement of one of said members with respect to the other and thereafter quickly move the lever member to another position, means for bodily moving one of said members relative to the other, and means for yieldingly resisting the movement of the 45 first means throughout a certain portion of the movement thereof and being ineffective throughout another portion of the movement of said first means.

4. In a switch, the combination with a supporting frame, of a pressure responsive device having a movable wall and an operating member associated therewith, a cage for said device including legs extending through openings within the frame and each having shoulders engaging opposite sides of said frame, and common means for preventing lateral movement of said legs.

5. In a switch, the combination with a supporting frame, of a pressure responsive device having a movable wall and an operating

member associated therewith, a cage for said device including legs extending through openings within the frame and each having shoulders engaging opposite sides of said frame, and a plate between said legs for preventing lateral movement of the latter.

6. In a switch, the combination with a supporting frame, of a pressure responsive device having a movable wall and an operating member associated therewith, a cage for said device including legs extending through openings within the frame and each having shoulders engaging opposite sides of said frame, a plate between said legs for preventing lateral movement of the latter, and common means for maintaining said plate and said device in position.

7. In a switch, in combination with a supporting frame; of an operating member; a unit including a pressure responsive device located on one side of the frame and having a movable wall associated with said member, a coupling located on the opposite side of frame, and a conductor connecting said coupling and device; a cage for said device including legs extending through openings within the frame and each having shoulders engaging opposite sides of the frame; a plate interposed between said legs for preventing the lateral movement of said legs; and means for maintaining said plate and said device in position, said plate and frame having openings permitting the passage of the coupling therethrough whereby said device, conductor, and coupling may be removed as a unit.

8. In a switch, the combination with an operating member; a pressure responsive device having a movable wall associated with said member; a support; and means for adjusting said device including a movable member extending through said support, adjustable members on opposite sides of said support each co-operating with the movable member, and a plurality of yielding means connected between the adjustable members and the support.

9. In a switch, the combination with an operating member; a pressure responsive device having a movable wall associated with said member; a support; and means for adjusting said device including a movable member extending through said support, adjustable members on opposite sides of said support each co-operating with the movable member, and springs on opposite sides of the support, each spring being interposed between the support and an adjustable member.

10. A switch comprising, in combination, a movable contact, a lever for actuating said contact; means for snapping said lever to open contact position, said means having a dead center with the lever, a lost motion connection between said lever and contact including a loosely fitting connecting pin, and a

70

115

120

125

130

spring engaging said pin for yieldingly maintaining said contact in closed position while said lever and means are in dead center position.

11. A switch comprising, in combination, a contact actuating lever member, an actuating member for the lever member, one of said members having a plurality of camming surfaces, and the other of said members being adapted to cooperate with one of the camming surfaces and tending to yieldingly maintain the lever member in a certain position throughout a certain bodily movement of one of said members with respect to the other and being adapted to cooperate with another of said camming surfaces for quickly rocking said lever member when the members are relatively bodily moved to a certain position, means for bodily moving one of said members relative to the other, and a resistance device arranged to resist movement of said means when the said other member cooperates with one of the camming surfaces and being ineffective throughout the latter portion of the movement between the said other member and the other of the camming surfaces. 70

12. A switch comprising, in combination, a contact actuating lever member having a plurality of camming surfaces, an actuating member for said lever member adapted to cooperate with one of the camming surfaces and thereby tending to yieldingly maintain the lever member in a certain position throughout a certain bodily movement of one of said members with respect to the other and being adapted to cooperate with another of said camming surfaces for quickly rocking said lever member when the members are relatively bodily moved to a certain position, means for bodily moving one of said members relative to the other, and a resistance device arranged to resist movement of said means when the said other member cooperates with one of the camming surfaces and being ineffective throughout the latter portion of the movement between the said other member and the other of said camming surfaces. 90

13. A switch comprising, in combination, a movable contact, a lever for actuating said contact, means for snapping said lever to open contact position, said means having a dead center with the lever, a lost motion connection between said lever and contact including a hollow link, a spring within the hollow link, a loosely fitting connecting pin, said spring engaging the pin for yieldingly maintaining said contact in closed position while said lever and means are in dead center position. 105

14. A switch comprising, in combination, a movable contact, a lever for actuating said contact, means for snapping said lever to open contact position, said means having a dead center with the lever, a lost motion connection between said lever and contact including a hollow part, a coil spring within 110

said hollow part, a connecting pin loosely connected with said part and extending transversely to said coil spring, said spring engaging the pin for yieldingly maintaining said contact in closed position while said lever and means are in dead center position. 125

15. A switch comprising, in combination, a plurality of contacts, a contact actuating member connected with one of said contacts and movable in opposite directions, means for resisting movement of said actuating member including a spring and a member engaged by the spring and lying in the path of movement of the actuating member, an externally threaded member and an internally threaded member cooperating to provide a casing for said spring, one of said threaded members engaging said spring and being adapted to vary the tension thereof. 130

16. A switch comprising, in combination, a plurality of contacts, a contact actuating member connected with one of said contacts and movable in opposite directions, means for resisting movement of said actuating member including a spring and a plunger having a shoulder engaged by the spring and arranged in the path of movement of the actuating member, an externally threaded member and an internally threaded member cooperating to provide a casing for said spring and adapted to receive the plunger, one of said threaded members engaging said spring and being adapted to vary the tension thereof. 140

17. A switch comprising, in combination, a plurality of contacts, a contact actuating member connected to one of said contacts and movable in opposite directions, means for resisting movements of said actuating member including a spring and a member engaged by the spring and lying in the path of movement of the actuating member, said spring engaged member having a shoulder for limiting the movement thereof, an externally threaded member and an internally threaded member cooperating to provide a casing for said spring, one of said threaded members engaging said spring and being adapted to vary the tension thereof. 150

18. A switch comprising, in combination, relatively stationary and movable contacts, a quick break device for said contacts including a lever member associated with the movable contact, an actuating member associated with said lever member, means for bodily moving one of said members relative to the other, said actuating member having a dead center position with the lever member and tending to hold said lever member in contact-making position until said means has moved said members to the dead center position and tending to quickly move said lever member to actuate the movable contact after said means has moved the members beyond the dead center position, and spring means be- 160

120

tween the lever member and movable contact for maintaining said movable contact in engagement with the other contact when said members are in dead center position.

- 5 19. A switch comprising, in combination, relatively stationary and movable contacts, a quick break device for said contacts including a lever member associated with the movable contact, an actuating member associated with said lever member, means for bodily moving one of said members relative to the other, said actuating member having a dead center position with the lever member and tending to hold said lever member in contact-making position until said means has moved said members to the dead center position and tending to quickly move said lever member to actuate the movable contact after said means has moved the members beyond the dead center position, and means for maintaining said contacts in engagement while said members are in dead center position, said last means including a spring constantly urging the contacts toward one another.
- 10 20. In testimony whereof I hereto affix my signature.
- 15 25.
